(57) **CLAIM**

The ornamental design for an out only rodent blocker, as shown and described.

DESCRIPTION

FIG. 1 is a front perspective view of the out only rodent blocker;

FIG. 2 is a top plan view of the invention;

FIG. 3 is a bottom plan view of the invention;

FIG. 4 is a front elevation view of the invention;

FIG. 5 is a rear elevation view of the invention;

FIG. 6 is a right end elevation view of the invention;

FIG. 7 is a left end elevation view of the invention; and,

FIG. 8 is a front elevation view of the invention in use.
The broken lines in the drawings represent unclaimed environmental subject matter and form no part of the claim.
